UNITED STATES PATENT OFFICE.

RICHARD HERVIG, OF CHICAGO, ILLINOIS, ASSIGNOR TO AMERICAN CAR AND FOUNDRY COMPANY, OF NEW YORK, N. Y., A CORPORATION OF NEW JERSEY.

GRINDING MACHINE.

Application filed March 21, 1922. Serial No. 545,457.

To all whom it may concern:

Be it known that I, RICHARD HERVIG, residing at Chicago, Cook County, State of Illinois, and being a citizen of the United States, have invented certain new and useful Improvements in a Grinding Machine, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

In said drawings:

Fig. 1 is a side elevation of my improved grinding machine, part being broken away to show details;

Fig. 2 is a front elevation of my device, the tail stock being broken away and the head stock and grinding spindle bearings and grinding wheel casing being shown in section;

Fig. 3 is a top plan view with the tail stock and a gear casing shown in section;

Fig. 4 is a vertical section, taken on line 4-4 of Fig. 5, showing part of the operating and adjusting mechanism;

Fig. 5 is a vertical section taken on the line 5-5 of Fig. 4;

Fig. 6 is a detail sectional view of a part of the operating mechanism; and

Fig. 7 is a detail sectional view of a part of the means for operating the cross slide.

It is an object of my invention to provide an improved grinding machine and, more particularly, to provide an improved means for operating the table carrying the head and tail stocks of a grinding machine. It is also an object of my invention to provide a means whereby a table of the kind described may have its extreme positions and its length of movement varied when operated by an operating means having a uniform stroke.

With these and other objects in view, my device comprises a suitable base 1 carrying the table 2, of a cross slide, mounted for reciprocation on the base 1 and having mounted thereon bearings 3 supporting a spindle 4. The spindle 4 is driven by a pulley 5

and carries a grinding wheel 6 which rotates in a shield 7. Water for the wheel 6 is supplied by a pipe 8 supported by a bracket 9 attached to the shield 7. Mounted on the base 1 for reciprocation at right angles to the line of movement of the table 2 is a table 10 having a head stock 11 and a tail stock 12 adjustably secured thereto by bolts 13, the heads of which engage in a slot cut in the surface of the table 10. The head stock 11 comprises a spindle 14 carrying a face plate 15 and a pulley 16 and supported in bearings 17 while the tail stock comprises a plunger 18, pressed forward by a spring 19 and adapted to be retracted by a lever 20.

In order that the table 2 may be reciprocated on the base 1, there is secured to the underside of the table 2 a rack 21 that engages a gear 22 on a shaft 23 mounted in bearings carried by the base 1. Mounted on the shaft 23 is a worm wheel 24 engaged by a worm 25 on a shaft 26 mounted on bearings in the base 1. A hand wheel 27 serves to operate the shaft 26 and through the worm 25, gears 24 and 22 and rack 21, to reciprocate the grinding wheel 6 on the base 1. To steady the operation of the grinding wheel, a weight 28 is attached to the table 2 by a cable 29 passing over a pulley 30 carried in a bracket 31 secured to the base 1.

To reciprocate the table 10 there is provided a lever 32 journaled, at one end, on a stub axle 33 mounted in a boss 34 cast integral with the base 1. The lever 32 is provided with a rectangular slot 35, intermediate its ends, in which slides a rectangular bearing block 36. Journaled in the block 36 is a crank arm 37 carried by a gear 38 that is mounted on a shaft 39 journaled in a bearing 40 formed in the base 1. Engaging the gear 38 is a pinion 41 mounted on a sleeve 42 that is supported on bearings in the base 1 and is provided with a hand wheel 43. Rotatably mounted in the sleeve 42 and in bearings in the base 1 is a shaft 44 carrying a gear 45 and having a reduced and screw-threaded end 46. Mounted on the threaded end 46 is a clutch member 47 having a conical surface that is adapted to engage with a correspondingly shaped surface formed on the sleeve 42. Operating the clutch member 47 to engage with the sleeve 42 will cause the shaft 44 and sleeve 42 to operate together while retracting the clutch member 47 will release the shaft 44 from the

sleeve 42. Engaging with the gear 45 is a gear 48 mounted on a shaft 49. The shaft 49 is supported in bearings in the base 1 and carries a pulley 50 so that the table 10 may be operated from any suitable source of power as well as by means of the hand wheel 43.

If the table 10 were connected directly to the lever 32 the extent of the movement 10 of the table 10 and the extreme positions assumed by the table would be uniform as the extent of the movement of the lever 32, when operated by either the pulley 50 of the hand wheel 43, is uniform; so in order that 15 the amount of movement and the extreme positions of the table 10 may be varied, the upper end of the lever 32 is provided with a rectangular slot 51 in which a rectangular bearing block 52 is adapted to slide. The 20 lever 32 and block 52 are received between the downwardly projecting arms 53 and 54 formed integral with the table 10 and adapted to travel in an opening 55 in the base 1. Mounted in the arms 53 and 54, so 25 as to travel in a slot 56 in the base 1, is a tubular sleeve 57 having a cylindrical portion rotatably mounted in an opening 58 in the arm 53 and a cylindrical portion 59, of smaller diameter, rotatably mounted in 30 a bushing 60 that is held against rotation in the opening 61 in the arm 54 by the key 62. The portion 72 of the sleeve 57 that passes through the bearing block 52 is also cylindrical but its axis is displaced with respect to the axis of the rest of the sleeve, but parallel thereto, and the portion of the sleeve that projects beyond the base 1 is provided with a hand wheel 63 by which the sleeve 57 may be operated. Slidably 35 mounted in the bore 64 of the sleeve 57 is a plunger 65 which has a reduced portion 66 projecting through a plug 67 which closes the bore 64 and threaded at its outer end to receive an adjusting nut 68. The plunger 40 65 is held against rotation in the sleeve 57 by a key 69 and has fixed thereon, a toothed clutch member 70 adapted to engage correspondingly shaped teeth formed in the outer face of the bushing 60. Rotation of 45 the nut 68 in one direction will cause the plunger 65 to travel in the sleeve 57, against the action of spring 71 so as to bring the clutch member 70 into engagement with the bushing 60 and the sleeve 57 will be held 50 against rotation with respect to the arms 53 and 54. Rotating the nut 68 in the opposite direction will release the plunger 65 so that the spring 71 may slide the plunger in the sleeve 57 and disengage the clutch member 70 from the bushing 60. With the 55 clutch member 70 disengaged from the bushing 60 the sleeve 57 may be rotated in the arms 53 and 54 causing the portion 72 of the sleeve 57 to act as a cam and to shift the bearing block 52 with respect to the lever 32

and with respect to the arms 53 and 54. It will be noted that as the axis of the portion 72 is shifted to one side or the other of a vertical plane through the axis of the remainder of the sleeve 57 that the position of the arms 53 and 54, with respect to the lever 32, will be changed so that the position of the table 10 at each limit of its movement will be changed. It will also be noted that as the axis of the portion 72 is shifted to one side 75 or the other of a horizontal plane through the axis of the remainder of the sleeve 57 that the bearing block 52 will be moved in the slot 51 in the lever 32, thus varying the effective length of the lever 32 and varying the amount of movement of the table 10. It will also be noted that every adjustment of the portion 72 causes an adjustment of both the position of the block 52 in the slot 51 and the position of the arms 53 and 54 with 80 respect to the lever 32 so that means are provided whereby the limiting positions and movement of the table 10 may be readily adjusted. It will be apparent that the table 10 may be given the same extent of movement from different extreme positions or different extents of movement from the same extreme position or from different extreme positions. 90

What I claim is:

1. In a grinding machine, a table, a slotted oscillating lever having a uniform movement, a bearing block slidable in said slot and means carried by said table adapted to shift said block in said slot to vary the movement of said table. 95

2. In a grinding machine, a reciprocating table, a slotted oscillating lever having a uniform movement, a bearing block slidable in said slot and a rotatable cam carried by said table and adapted to shift said block in said slot and to shift said table with respect to said lever. 105

3. In a grinding machine, a table, arms projecting from said table, a slotted oscillating lever having a uniform movement, a bearing block slidable in said slot, a cam rotatably mounted in said arms and adapted to shift said block in said slot to vary the movement of said table and means for locking said cam against rotation. 110

4. In a grinding machine, a table, an oscillating lever for operating said table and means connecting said table and lever adapted to vary the extent of movement of the table. 120

5. In a grinding machine, a table, an oscillating lever for operating said table and means connecting said table and lever adjustable to give movements of said table of the same extent between different sets of extreme positions of said table. 125

6. In a grinding machine, a table, an oscillating lever for operating said table and means connecting said table and lever ad- 130

justable to vary the extent of movement and to give movements of the same extent between different sets of extreme positions of said table.

5 7. In a grinding machine, a table, a slotted lever for reciprocating said table, a bearing block slidable in said slot, and means connecting said block and table adapted to adjust the position of said block in said slot.

10 8. In a grinding machine, a table, a slotted lever, a bearing block slidable in said slot and a member connecting said block and table and having an eccentric portion adapted to move said block in said slot upon rotation of said member.

15 9. In a grinding machine, a table, arms projecting from said table, a slotted lever, a bearing block slidable in said slot, a rotatable member connecting said block and

arms and means for locking said rotatable member against rotation.

10. In a grinding machine, a table, arms projecting from said table, a lever pivoted at one end, means engaging said lever intermediate its ends and adapted to impart movements of uniform extent to said lever, a bearing block slidably engaging the lever at its other end, a rotatable member connecting said block and arms and means for locking said rotatable member against rotation with respect to said arms.

In witness whereof I have hereunto set my hand in the presence of two witnesses.

RICHARD HERVIG.
